UNITED STATES PATENT OFFICE.

JACOB LEE POTTS, OF ITHACA, MICHIGAN.

MOP-WRINGER.

No. 850,781.

Specification of Letters Patent.

Patented April 16, 1907.

Application filed June 20, 1906. Serial No. 322,613.

To all whom it may concern:

Be it known that I, JACOB LEE POTTS, a citizen of the United States, and a resident of Ithaca, in the county of Gratiot and State 5 of Michigan, have invented a new and Improved Mop-Wringer, of which the following is a full, clear, and exact description.

The invention relates to washing and scrubbing; and its object is to provide a new and 10 improved mop-wringer arranged to permit of conveniently and quickly placing the mop in position between the mop-wringing rolls to insure a proper wringing of the mop.

The invention consists of novel features 15 and parts and combinations of the same, which will be more fully described hereinafter and then pointed out in the claims.

A practical embodiment of the invention is represented in the accompanying drawings, 20 forming a part of this specification, in which similar characters of reference indicate corresponding parts in all the views.

Figure 1 is a plan view of the improvement, part being removed and part in section. 25 Fig. 2 is a sectional side elevation of the same on the line 2 2 of Fig. 1. Fig. 3 is a transverse section of the bearing for one of the wringing-rolls, the section being on the line 3 3 of Fig. 2. Fig. 4 is a plan view of a modified form of the improvement, and Fig. 5 is a side elevation of the folded frame.

The frame A of the mop-wringer is preferably made foldable for convenient storing or for transporting and for this purpose consists of a skeleton top A' removably connected with the upper ends of standards A² by screws B, and in the lower ends of the standards A² are secured pivots A³, engaging bearings A⁴, attached to the under side of a platform A⁵, for supporting a pail C of any approved construction. Now by removing the screws B the standards A² are disconnected from the top A'. The said standards can then be folded one on top of the other with 45 the platform A⁵ extending between the standards, as indicated in Fig. 5.

In the top A' of the frame A are arranged the mop-wringing rolls D and D', between which the mop E is passed and which are 50 arranged above the pail C, so that drippings from the mop E drop down in the pail C. One of the rolls, preferably the roll D, is provided with a crank D², under the control of the operator for turning the roll, so as to cause 55 an easy traveling of the mop E between the rolls D and D'. The roll D is journaled in

suitable bearings F, held adjustable lengthwise in a guideway A⁶, formed in the top A' by the use of set-screws F', and the roll D' is journaled in bearings G, mounted to slide 6c freely in the said guideways A⁶. Now in order to hold the roll D' in position against the mop E at one side thereof, so as to press the mop firmly between the rolls D and D', a spring H is provided, having its terminals H' 65 attached to the bearings G, the terminals leading to coils H², which in turn are connected with each other by a cross-bar H³, being pivotally connected with an arm I' on a lever I, provided at its free end with a handle I² and pivotally connected at its other end with a cross-bar J' on a spring J, having coils J² attached by staples K or like devices to the top A' of the frame A. The terminals of the spring J' rest against pins or bolts K', 70 preferably some of the bolts used for holding the top pieces of the guideways A⁶ in position on the top A' of the frame A. The bearings G are also connected with each other by a cross-bar G', which forms a stop for the free 75 end of the lever I when the latter is in an active position—that is, swung downward, so that the springs H and J are put under tension to cause the bearings G to press the roller D' in firm contact with one side of the 80 mop E. When the operator takes hold of the free end of the lever I and swings the same upward into the position shown in dotted lines in Fig. 2, then the springs H and J are released and at the same time the bearings G are drawn rearwardly to free the 85 roller D' of the mop E, thus allowing convenient removal thereof or insertion of the same between the rollers D and D'.

In the modified form shown in Fig. 4 the 90 lever I' is pivotally connected with the horizontally-disposed coils L' and N' of two springs L and N, of which the spring L has its terminals attached to the guideways G² for the roller D⁴ operating in conjunction 95 with the roller D³ held in the bearings F², similar to the roller D, previously mentioned and likewise provided with a crank-arm D⁵ for turning the roller. The other spring N has its terminal secured in the top A' of the 100 frame A, and the bearings G² are connected with each other by a cross-bar G³, forming a stop for one end of the lever I' when the latter is in a closed position—that is, when the springs L and N are under tension, as indicated in Fig. 4.

From the foregoing it will be seen that the

single lever I or I^3 serves to place two springs simultaneously under tension so as to hold the roller D' or D in yielding contact with the mop E, so as to properly wring the same when the roller D is turned and the mop is caused to travel between the rollers D D' or $D^3 D^4$.

The mop-wringer shown and described is very simple and durable in construction and can be conveniently folded for transportation or storing purposes. By having the pail C entirely separate from the mop-wringer device it is evident that any ordinary pail can be used and the device need not be attached to the pail, as is frequently the case with mop-wringers as heretofore constructed.

I do not limit myself to the particular construction of the mop-wringer shown and described, as the same may be varied without deviating from my invention.

20 The mop-wringer may be attached to the top of a pail, in which case the folding frame would not be used. The springs may be made with or without coils and of either wood or steel. When made straight of either 25 wood or steel, the forward spring would be connected with the lever I at the point H^3 by means of bars, having holes in either end, forming a hinged point on the spring, and an elbow-joint on the lever I at the said point H^3 .

30 Having thus described my invention, I claim as new and desire to secure by Letters Patent—

35 1. A mop-wringer, comprising a frame, wringing-rolls, bearings for one of the wringing-rolls and fixed in the said frame, bearings 40 slidable in the said frame and in which the other wringing-roll is journaled, springs, and a lever for placing the springs under tension, one of the springs being held on the frame and the other having its terminals engaging the said slidable bearings.

45 2. A mop-wringer, comprising a frame, wringing-rolls, bearings for one of the wringing-rolls fixed in the said frame, slidable bearings in which the other wringing-roll is journaled, springs, of which one is connected

with the frame and the other having its ends engaging the said slidable bearings, and a lever fulcrumed on the said spring attached to the frame and pivotally connected with the 50 said spring connected with the slidable bearings.

3. A mop-wringer, comprising a frame, wringing-rolls, bearings for one of the wringing-rolls fixed in the said frame, slidable bearings in which the other wringing-roll is journaled, springs, of which one is connected with the frame and the other with the said 55 slidable bearings, a lever fulcrumed on the said spring attached to the frame and pivotally connected with the said spring connected with the slidable bearings, and a stop-rod for the lever and attached to the said slidable bearings.

4. A mop-wringer, comprising a frame, 60 rollers mounted in the frame, sliding bearings for one of the rollers, a spring having its ends secured to the frame, a second spring having its ends engaging the sliding bearings, and a lever fulcrumed on the first-named spring and provided intermediate of its ends with an arm pivotally connected with the second spring.

5. A mop-wringer, comprising a frame, 65 rollers mounted in the frame, sliding bearings for one of the rollers, a spring having its ends secured to the frame, a second spring having its ends engaging the sliding bearings, a lever fulcrumed on the first spring and provided intermediate of its ends with a 70 downwardly-extending arm pivotally connected with the second spring, and a rod connecting the sliding bearings and serving as a stop for said lever.

In testimony whereof I have signed my 85 name to this specification in the presence of two subscribing witnesses.

J. LEE POTTS.
